US00D824368S

(12) **United States Design Patent** (10) **Patent No.:** **US D824,368 S**
(45) **Date of Patent:** **** Jul. 31, 2018**

(54) **REMOTE CONTROL FOR A COMPUTING DEVICE**

(71) Applicant: **LARC Networks, Inc.**, Los Altos, CA (US)

(72) Inventors: **Martin Kacin**, Los Altos Hills, CA (US); **Steve Eckland**, Palo Alto, CA (US); **Robert Alexander Garrow, Jr.**, Los Altos Hills, CA (US); **Kirk Lynn Reistroffer**, Fremont, CA (US)

(73) Assignee: **LARC Networks, Inc.**, Los Altos, CA (US)

(**) Term: **15 Years**

(21) Appl. No.: **29/566,123**

(22) Filed: **May 26, 2016**

(51) LOC (11) Cl. **14-03**

(52) U.S. Cl.

USPC **D14/218**

(58) **Field of Classification Search**

USPC D14/218, 225, 204-206, 454; D13/168; D10/49; D21/333

CPC .. H04N 7/17318; H04R 1/083; G06F 1/1628; G06F 3/01; G06F 3/16

(57) **CLAIM**

We claim the ornamental design for a remote control for a computing device.

DESCRIPTION

FIG. 1 is a perspective view for a remote control for a computing device;

FIG. 2 is a second perspective view thereof;

FIG. 3 is a top view thereof;

FIG. 4 is a bottom view thereof;

FIG. 5 is a rear view thereof;

FIG. 6 is a front view thereof;

FIG. 7 is a left side view thereof; and,

FIG. 8 is a right side view thereof.

The broken lines illustrate portions of the remote control for a computing device which form no part of the claimed design.

1 Claim, 8 Drawing Sheets
